UNITED STATES PATENT OFFICE.

WILLIAM F. SCHWEIGER AND BENNETT D. STRAIGHT, OF ROCHESTER, NEW YORK,
ASSIGNORS, BY DIRECT AND MESNE ASSIGNMENTS, TO MULTIPOST COMPANY, OF
ROCHESTER, NEW YORK, A CORPORATION OF NEW YORK.

STAMP-AFFIXER.

999,884.

Specification of Letters Patent. Patented Aug. 8, 1911.

Application filed November 21, 1910. Serial No. 593,322.

To all whom it may concern:

Be it known that we, WILLIAM F. SCHWEIGER and BENNETT D. STRAIGHT, of Rochester, in the county of Monroe and State of New York, have invented certain new and useful Improvements in Stamp-Affixers; and we do hereby declare the following to be a full, clear, and exact description of the same, reference being had to the accompanying drawings, forming a part of this specification, and to the reference-numerals marked thereon.

The present invention relates to stamp affixers and has for its object to provide certain improvements in connection therewith for preventing the surreptitious removal of the stamps.

To this end the invention contemplates an arrangement of the parts whereby the removal of a stamp from the guide way in any other way than by the actual operation of the machine, will render the latter inoperative.

One embodiment of the invention consists in arranging the parts of the guide way or channel through which the stamps are fed so that they may be projected successively into affixing position by the feeding mechanism, but will be arrested in the event an attempt is made to extract them by means other than the action of the feeding mechanism.

To these and other ends the invention consists in certain improvements and combinations of parts all as will be hereinafter more fully described, the novel features being pointed out in the claims at the end of the specification.

In the drawings: Figure 1 is a vertical sectional view of a stamp affixing mechanism illustrating the application thereto of a mechanism embodying the present invention; Fig. 2 is a horizontal sectional view of the guide way taken on the line 2^x—2^x of Fig. 1; Fig. 3 is a side elevation of the stamp container and guideway removed from the machine; Figs. 4 and 5 are detail sectional views taken on the line 4^x—4^x of Fig. 3, illustrating the operations of the parts when actuated to prevent the removal of stamps; Fig. 6 is a sectional view showing a modified form of stamp arresting mechanism.

Similar reference numerals throughout the several figures indicate similar parts. 55

This application is a continuation of the joint application for U. S. Letters Patent for improvements in stamp affixers, filed by us under date of June 6, 1910, bearing Serial No. 565,167, and in illustrating the present invention certain parts of the stamp affixer disclosed in said application have been shown to clearly illustrate the operation of the mechanism embodying the features of this invention. 60 65

The stamp affixer as a whole comprises the frame 1 in which is guided a vertical reciprocatory affixing member 2 which is normally retracted into inoperative position by a spring or springs 3, and projected downwardly into affixing position, through an aperture 4 provided in the base of the frame, by means of the shaft 5, on which said member is mounted, provided with a handle or knob 6 conveniently shaped to fit 70 75 the hand of the operator.

The feeding devices by which the stamps are projected into the path of the affixing member comprise a plurality of fingers 7, arranged side by side and coöperating with 80 the stamp strip guide way. The feeding devices are supported upon a carriage 8 in the form of a sleeve surrounding the shaft 5, and adapted to reciprocate therewith.

At one side of the frame is mounted a 85 small tank or liquid container 9 from which water or other liquid may be ejected, through small apertures (not shown) located at the lower end of the tank, by means of a piston operating therein, the extremity 90 of which projects exteriorly of the tank, as indicated at 10. Coöperating with the latter is a spring 11 having a cam surface 12 thereon which coöperates with a spring latch 13 arranged in the face of the affixing member 2, as shown in dotted lines.

The stamp guide way to which the present invention is particularly directed, is adapted to conduct the stamp strip from a suitable receptacle to a point of discharge 100 near the lower end and at one side of the path of movement of the affixing member 2, and as the latter is also designed to cut or sever the projected stamp, the extremity of the guide way leads to the cutting bar 14 105 which is provided with a suitable aperture,

forming a continuation of the guide way, across which the cutting edge or knife 15 on the affixing member passes when the latter is depressed downwardly into affixing position.

In machines of this character it is essential that means be provided to prevent the unauthorized removal of the stamps, and also to render the machine inoperative in the event such an attempt is made, and to this end the guide way is constructed with a portion which is adapted to impart a continuous normal curve to the stamp strip as it passes along the guide way. Coöoperating with the latter is an arresting member so positioned that it is normally inoperative, the curved part of the stamp strip passing at one side of said member unobstructedly. The shape of the guide way and the portion of the arresting member is such that any attempt to withdraw the stamp strip by pulling its free end will cause it to be deflected into engagement with the member which will afterward securely hold the strip and prevent it from being advanced by the subsequent action of the feeding mechanism.

In the illustrations of the type of apparatus adopted as a commercial form of apparatus which includes one embodiment of the invention, the following arrangement of parts has been shown: Removably attached to one side of the frame is a receptacle 15* adapted to contain the rolled stamp strip indicated by 16, the extremity of which passes downwardly into the guide way through the aperture or throat 17. The receptacle and guide way are preferably connected together to form a single member or element of the machine so that these parts may be readily detached when it becomes necessary to reload the receptacle or disengage the stamp strip from the arresting member. To this end a supplemental frame piece or leg comprising the side pieces 18 and 19 and the back piece 20, depends from the receptacle 15 and at their lower end these parts inclose a key operated lock having a bolt 21, securing the receptacle and guide way to the frame 1. In the drawings the receptacle is also shown provided with ears or fingers 22 adapted to be hooked in rear of a projection 23 at the upper end of the frame, which together with the lock hold the receptacle and guide way in operative position. The guide way comprises the backing or stationary member 24 which forms its outer side, and spring arms 25 forming its inner side, and bearing lightly against the face of the stamp strip at its edges.

The guide way throughout a portion of its length extends in a direction parallel to the direction of movement of the feeding mechanism or fingers 7 so that during the downward or advancing movement of the

latter the strip may be fed forwardly a distance equal to the length of a single stamp, the guide way as a whole being of a sufficient length to cause a portion of the strip, equal to the length of two or more stamps, to be always projected or pushed ahead of the feeding devices. At its lower end the guide is curved, as indicated at 24* for the purpose of directing the free end of the stamp strip to one side of or laterally to the direction of its feeding movement. The spring arms 25 are attached at their upper ends to the outer side of the wall of the receptacle or container 15*, by means of rivets or other suitable fastening devices, indicated by 26, from which point they curve downwardly to form an open throat beneath the aperture 17, in which the end of the stamp strip may be easily inserted, and thence along the lateral edges of the stationary guide member 24 to the beginning of the curved portion of the guide. From this point the springs instead of following the curve extend in a substantially straight line to a point near the extremity of said curved portion where their ends are rounded over or curved upon themselves, as indicated at 27. It will be seen that the straight portions of the arms 25 extend as chords across the segment of the circle described by the guide, and instead of hugging the curved part of the latter bear against it at two separated points. This is sufficient to hold the stamp strip lightly in engagement with the back of the guide way and as the strip is pushed or shoved around the curve it will naturally lie flat against the part 24*, or should the paper be a trifle stiff the friction imparted to it by the lower ends of the spring arms 25 will retard the movement of its forward end sufficiently to cause the paper to be flattened against the curved portion of the guide. The spring fingers 25 bear lightly against the stamp strip so that only a slight pull on its outer end will be sufficient to disturb its normal position and draw it out of engagement with the backing 24. The means for arresting the stamp strip when thus deflected comprises in the present instance, two impaling pins or needles 28 and 29, their location being generally described as at the inside of the portion of the stamp strip which is curved by the guide way, although it will be understood they may be otherwise arranged, the intention being to so position them that they will engage the stamp strip when it is pulled forwardly in the guide way. The arresting member is supported upon spring fingers 30 and 31 carried on the arms 25 to which the fingers are secured at their upper ends, as indicated at 32.

The impaling pins or needle points normally rest in rear of the fingers 25 and are adapted to be brought into action, by pro-

jecting through slots or apertures 33 provided in the arms 25, when the lower ends of said arms are moved outwardly. Spring tension is imparted to the arms 25 in a direction to cause them to normally move toward the back or stationary part of the guide way, and tension is also provided in the fingers 30 and 31 to move the impaling pins rearwardly into engagement with shoulders or stops 34, projecting inwardly from the side walls 18 and 19 of the supplemental frame in which said guide is supported. These stops, it will be noticed, are so positioned that when the stamp strip is pulled forwardly and deflected from the back of the guide way, as shown in Fig. 4, which may be easily done by a strain on the strip less than that required to tear off a stamp, the strip will be drawn into engagement with the needle points. The latter are also set at an angle to the direction of movement of the stamp strip so that the pulling tension thereon will cause it to become firmly caught and this angular position of the needle points also serves to retain them in engagement with the strip when the pulling tension on the latter is released and the arms 25 are allowed to return to their normal position with the consequent result that the impaling pins are moved toward the back of the guideway, the light spring tension of the supporting arms 30 and 31 permitting them to be carried away from the stops 34. This condition of the apparatus is a sure indication of an attempt to remove a stamp, as the strip being firmly held, resists the further action of the feeding device or fingers 7, which if subsequently operated will merely cause the next succeeding stamp in the strip to be wrinkled, as shown in Fig. 5. To restore the machine to operative condition the stamp receptacle and guide way must be removed by the authorized person possessing the key required to release the latch or bolt 21. These parts being detached, the arresting member or members may be disconnected either by the operator's finger, or a suitable instrument for retracting the needles, when the crumpled stamp may be smoothed out or removed.

It is obvious that deflecting or directing the free end of the stamp strip in a direction laterally to the movement of the feeding mechanism provides a certain amount of fullness or idle material between the extremity of the guide way and the feeding mechanism, which can be easily displaced by pulling the extremity of the stamp strip or tape, but as this object may be accomplished in other ways, we have shown in Fig. 6 another simple arrangement of the parts also falling within the purview of our invention. The illustration referred to is somewhat diagrammatic, the guide way be-

ing shown as comprising a back *a* over which the stamp strip or tape *b* is passed, it being projected in the direction toward the right hand end of the figure, by means of a reciprocating feeding finger *c*. At some 70 point in the length of the guide way in advance of the limit of movement of the feeding finger it is provided with an aperture *d* at each side of which are located spring fingers *e*, *e*, which are curved upwardly at 75 their approximate ends to impart a curve or wave to the stamp strip as it is advanced or pushed toward the discharge end of the guide way. The spring fingers over which the strip passes hold it lightly in this position but permit the tape to be flattened or deflected out of its normal position when its free end is pulled. Projecting into the aperture *d* is an impaling pin or needle point *f* carried on the spring finger *g* and held in 80 the desired position in reference to the curved portion of the stamp strip by a stop or projection *h*.

A stamp affixer constructed in accordance with this invention while particularly 85 adapted to be used for applying postage stamps to pieces of mail matter, is equally well adapted for other uses, one of which may be mentioned as label affixing, and for this reason it will be understood that where 90 the expression stamp strip has been employed either in the specification, or the claims appended hereto, it applies equally to postage stamps, labels or the like which may be arranged in strip form and are 95 adapted to be discharged successively from the machine.

In machines of this character a distinct advantage is obtained not only by locking the strip when it is pulled forward to prevent the removal of stamps, but also by rendering the machine incapable of further operation on subsequently feeding stamps, as the arresting of the strip in the first instance prevents the removal of more than 100 a single stamp and provides unmistakable evidence that an attempt was made to remove them.

We claim as our invention:

1. In a stamp affixer, the combination 115 with an affixing member, a guide way for stamp strips, having a portion adapted to impart a continuous normal curve to a stamp strip as it is fed therethrough, a feeding device adapted to coöperate with the stamp strip for advancing its free end along the guide, of an impaling pin located at the inner side of the curved portion of the strip and adapted to be engaged by the latter 120 when a sufficient tension is imparted to the free end of the strip to cause its curved portion to be deflected, said pin being movably supported and capable of being moved by the strip when the tension applied thereto 125 is removed. 130

2. In a stamp affixer, the combination with an affixing member, a guide way for stamp strips having a portion adapted to impart a continuous normal curve to a stamp strip as it is fed therethrough, a feeding device adapted to coöperate with the stamp strip for advancing its free end along the guide, of an impaling pin located at the inner side of the curved portion of the strip and adapted to be engaged with the latter when a sufficient tension is imparted to the free end of the strip to cause its curved portion to be deflected, said pin being inclined at an angle to the direction of movement of the stamp strip and capable of being moved by the strip when the tension applied thereto is removed.
3. In a stamp affixer, the combination with an affixing member, a guide way for stamp strips having a portion adapted to impart a continuous normal curve to a stamp strip as it is fed therethrough, a feeding device adapted to coöperate with the stamp strip for advancing its free end along the guide, of an impaling pin located at the inner side of the curved portion of the strip and adapted to be engaged by the latter when a sufficient tension is imparted to the free end of the strip to cause its curved portion to be deflected, said pin being movably supported and capable of being moved by the strip when the tension applied thereto is removed, and a spring finger coöperating with the inner side of the curved portion of the stamp strip for normally guiding the strip around said pin.
4. In a stamp affixer, the combination with an affixing member, a guide way for stamp strips having a curved portion, an impaling pin movably supported at the inside of said curved portion, and a movable finger engaging the stamp strip to yieldingly hold it out of engagement with said pin, of means for feeding the stamp strip along the guide way.
5. In a stamp affixer, the combination with an affixing member, a guide way for stamp strips having a curved portion, a yielding finger located at the inside of said curved portion for normally holding a stamp strip in engagement with the guide, of an impaling pin located behind the finger and movable toward the guide and means for feeding the stamp along the guide way.
6. In a stamp affixer, the combination with an affixing member, a guide way for stamp strips having a curved extremity, a yielding finger arranged at the inside of said curved
- part of the guide way, of an impaling pin located behind the finger, a separate finger 60 yieldingly supporting the pin and means for feeding a stamp strip along the guide way and advancing its free end around the curved end of the guide way.
7. In a stamp affixer, the combination with an affixing member, a guide way for stamp strips curved at its extremity to form a discharge end located at one side of the path of the affixing member and devices for pushing a stamp strip along the guide, of an impaling pin located at the inner side of the curved portion of the guide in a position to engage the stamp strip when the latter is displaced in the guide, said pin being yieldingly supported at an angle to the direction 75 of movement of the stamp strip.
8. In a stamp affixer, the combination with an affixing member, a guide way for stamp strips having a curved portion, feeding devices adapted to coöperate with a stamp strip 80 to push its extremity around said curved portion, of impaling pins located in juxtaposition to the edges of the guide way at the inside of the curved portion thereof, said pins being yieldingly supported and adapted 85 to engage the stamp strip when deflected in the curved portion of the guide.
9. In a stamp affixer, the combination with an affixing member, a guide way for stamp strips comprising a rigid backing provided 90 with a curved extremity, yielding arms forming one side of the guide way having their free ends extending at an angle across the inside of the curved portion of said backing and yielding fingers carried on the arms, 95 of impaling pins supported on said fingers and feeding devices for advancing a stamp along said guide way.
10. In a stamp affixer, the combination with a movable affixing member, a stamp 100 strip receptacle and a guide way leading therefrom, said guide way comprising a back piece extending from the receptacle and having a curved extremity, and a spring arm extending longitudinally of the back piece 105 and movable relatively thereto, of a spring finger carried on the arm and provided with an impaling pin, a stop for limiting the movement of the finger in one direction laterally of the guide way and devices for 110 feeding a stamp strip along the guide way.
